ATTORNEYS

UNITED STATES PATENT OFFICE.

WILLIE W. FARNSWORTH, OF BRUSHTON, NEW YORK.

SOLDERING APPARATUS.

1,005,010.

Specification of Letters Patent.

Patented Oct. 3, 1911.

Application filed March 14, 1911. Serial No. 614,339.

To all whom it may concern:

Be it known that I, WILLIE W. FARN-
SWORTH, a citizen of the United States, and a
resident of Brushton, in the county of
5 Franklin and State of New York, have
made certain new and useful Improve-
ments in Soldering Apparatus, of which
the following is a specification.

My invention relates to improvements in
10 devices for soldering parts, especially parts
of jewelry, optical goods, etc., and it con-
sists in the combinations, constructions and
arrangements herein described and claimed.

An object of my invention is to provide
15 a device by means of which two small parts
may be held rigidly, while the soldering
operation is conducted.

A further object of my invention is to
provide a small pad of heat insulating ma-
20 terial, which may be held in the hand while
the parts to be soldered may be securely
held upon the pad by devices which may
be easily manipulated to release or retain
the parts to be mended.

25 A further object of my invention is to
provide a pad having supporting devices
capable of holding the interchangeable
tools, such as tweezers or clamps, the sup-
porting devices being of such a nature that

30 the tools may be held in various positions.

Other objects and advantages will appear
in the following specification and the novel
features of the device will be particularly
pointed out in the appended claims.

35 My invention is illustrated in the accom-
panying drawings forming part of this ap-
plication in which—

Figure 1 is a plan view of the device
showing the parts in their operative posi-
40 tion, Fig. 2 is a section along the line 2—2
of Fig. 1, Fig. 3 is a perspective view of a
pair of tweezers for use with the pad, and
Fig. 4 is a perspective view of another form
of holding tool, which may be advanta-
45 geously employed.

In carrying out my invention I provide
a base 1 preferably of wood or other heat-
insulating material, upon which I mount
a pad 2 of non-combustible material, such as
50 asbestos. In order to retain the pad upon
the base 1, I provide a metal band or rim 3,
which extends around the base, and is se-
cured to it by means of brads 4. The pad
2 is cut to fit just inside of this rim 3, and
55 both the pad and the base are provided with

registering openings through which pass
copper rods, such as those shown at 5, 6,
7 and 8. The bottoms of these rods are
threaded, as shown at 5^a, 6^a, 7^a and 8^a to
receive thumb nuts 5^b, 6^b, 7^b and 8^b. The 60
rods 5 and 8 are longer than the rods 6 and
7 and are designed to receive adjustable
heads 9 and 10, respectively. In the present
instance, I have shown these heads as brass
cylinders provided with openings to permit 65
the passage of the rods 5 and 8 and having
set screws 9^a and 10^a, respectively, to clamp
the heads in position. The heads 9 and
10 are also provided with openings 11 and
12 respectively. A set screw 11^a is arranged 70
to pass into the opening 11 and a set screw
12^a is arranged to pass into the opening 12.
A brass spring 13 is disposed between the
head 9 and the pad 2 so as to press the head
9 and rod 5 upwardly. A similar spring 14 75
keeps the head 10 and rod 8 in an upper
position.

Secured to the upper ends of the rods
6 and 7 are the retaining devices 15 and
16 respectively. Obviously they may be of 80
other shapes than that shown in the draw-
ing. The heads 9 and 10 and the retaining
devices 15 and 16 are preferably made of
brass.

In Figs. 3 and 4, I have shown the tools 85
which are designed to coöperate with the
heads 9 and 10 in holding the work firmly
upon the pad. Thus in Fig. 3 a copper rod
17 is shown. This rod is designed to pass
through either of the openings 11 or 12 and 90
to be retained therein in adjustable positions
by means of the set screws 11^a and 12^a. The
outer end of the rod 17 is provided with a
loop 17^a, which is designed to receive a pair
of tweezers 18. These tweezers consist 95
merely of a pair of arms joined together by
an integral loop. Since the arms are thicker
at their ends than at the point where they
are united to the loop, it will be apparent
that the nearer the ends of the arms are to 100
the loop 17^a, the closer together the arms will
be forced so that when the arms are placed
over the part to be mended and the ends of
the arms are pushed toward the loop 17^a,
they will firmly clamp the article. In Fig. 105
4 I have shown a similar rod 17^b which is
provided with a downwardly curved portion
17^c having serrations at its end to prevent
the slipping of a part which it is designed
to retain.

From the foregoing description of the various parts of the device, the operation thereof may be readily understood.

Let us suppose it is desired to solder together a frame of a pair of nose glasses which have been broken. In Fig. 1, I have shown the nose glasses in position to be soldered. In order to hold the parts together, I have used two sets of tools, such as shown in Fig. 3. One of these parts X is first inserted in the tweezers 18, which are adjusted to clamp it securely, as already explained, and the rod 17 is then placed in the head 9 which is then rotated on the rod 5, the rod being pushed through the opening 11 until the piece to be held is in the proper position upon the pad. The set screws 9^a and 11^a are then tightened, and the thumb nut 5^b is then screwed up, so as to hold the piece securely upon the pad. A similar tool is then placed in the head 10 and adjusted to hold the other part Y of the article to be mended. The retaining devices 16 and 17 are then swung over those portions of the article which rest upon the pad and the thumb nuts 6^b and 7^b are tightened to provide additional holding members. It will be of course understood that the joint between the parts is first arranged in the position in which it is to be soldered.

The soldering operation may then be proceeded with while the pad is held in the hand and the pad may be turned without any danger of the parts becoming loosened or moving from their relative positions. When the operation is over, it is only necessary to unloosen the thumb nuts 5^b, 6^b, 7^b and 8^b and tweezers 18 when the article can be immediately removed.

It will be seen that I have provided a pad, which is extremely light, but which will firmly retain the parts in position during the soldering operation. The rods 5, 6, 7 and 8 are made of copper, as are also the tools 17 and 18. Acids may be used with these tools which would corrode iron, but which will not corrode the copper parts. When the pad 2 becomes worn, or if for any

other reason it is desired to change the pad, all that it is necessary to do is to remove 50 the thumb nuts, pull out the rods, bore holes in another pad and place the new pad in position. Obviously other tools of other shapes than those shown might be used with the rotatable heads 9 and 10, without 55 departing in the least from the spirit and the scope of the invention.

I claim:—

1. A soldering apparatus comprising a nonconducting base of light material having 60 perforations, a metallic rim secured to the edges of said base and arranged to project upwardly therefrom, a pad of heat-insulating material disposed within the rim upon said base and being provided with openings 65 arranged to register with those in the base, a series of rods arranged to extend through said openings, said rods being threaded at one end, a series of thumb nuts for said rods, heads provided with openings disposed 70 on certain of said rods, each head being rotatably and longitudinally adjustable with respect to its rod, springs for normally holding said heads in position, and interchangeable clamping tools having portions arranged to enter openings in said heads and to be adjustably retained therein.

2. In a soldering apparatus, a nonconducting base, a rim therefor, an insulating pad disposed upon said base within said rim, 80 said base and said pad being provided with registering openings, a series of rods disposed in said openings, the lower ends of said rods being threaded to receive thumb nuts, and clamping devices carried by the 85 upper ends of said rods, said rods being arranged to be moved longitudinally by means of the thumb nuts and said clamping devices being arranged to rotate with said rods to permit their adjustment into various positions with respect to the pad.

WILLIE W. FARNSWORTH.
